REFRIGERATION SYSTEM

William L. McGrath, Syracuse, N. Y., assignor to
Minneapolis-Honeywell Regulator Company,
Minneapolis, Minn., a corporation of Delaware

Application August 26, 1943, Serial No. 500,043

8 Claims. (Cl. 62—3)

1

The present invention relates in general to control means for a refrigeration system.

A conventional refrigeration system may achieve a measure of control by operating or stopping a compressor in response to a condition of the medium being cooled and by using a thermostatic expansion valve to control the flow of refrigerant to the evaporator. Limit devices comprising a cut-out opened by excessive head pressures and a cut-out opened by abnormally low suction pressures are sometimes connected in series with the compressor control means to prevent injury to the mechanism. The control system thus outlined is sufficient for some installations, but is not adequate for other applications, especially under conditions of light load. With light loads and a throttled flow of refrigerant, the evaporator is pumped down quite rapidly and "short cycling" takes place. Attempts have been made to prevent "short cycling" by throttling the suction, but this may cause abnormally low suction pressure at the compressor and result in mechanical difficulties.

Other attempts at control have included the use of a by-pass from the hot gas line to the suction line, but this has resulted in gases of excessively high temperature damaging the compressor. The present system supplements the control exercised by a thermostatic expansion valve over an evaporator by by-passing hot gaseous refrigerant around the condenser and through said evaporator.

It is, therefore, an object of the present invention to improve the control of a refrigeration system by by-passing gaseous refrigerant around the condenser and passing same through the evaporator.

It is a further object to control the conditions under which cooling may take place by preventing the evaporator pressure and temperature from dropping below a predetermined point, said pressure being maintained by by-passed gaseous refrigerant.

The by-pass system of control as previously known is not well adapted to multiple fixture operation, for the building up of suction pressure by any one of a plurality of by-passes affects the suction pressure of each of the evaporators. It is thus a further object of this invention to provide a system of control utilizing by-passed refrigerant which may be used with multiple fixture installations.

It is a further object of this invention to supplement the control of a thermostatic expansion valve over an evaporator by varying the quality

2

of the refrigerant passed through said thermostatic expansion valve.

The old by-pass system of control, as applied to a refrigeration system, frequently results in over-heated gases being supplied the compressor, but this difficulty is obviated in the present instance by passing the by-passed refrigerant through the evaporator where said gases are cooled by the expanding liquid refrigerant associated therewith. It is, therefore, an object of this invention to provide a system of by-pass control for a refrigeration system in which the gases in the suction means are maintained at a safe temperature.

It is a further object of the present invention to supplement the control of a thermostatic expansion valve by passing both liquid and gaseous refrigerant through a fixed orifice preceding said expansion valve. Other objects of this invention will become apparent from the following description and from the appended claims.

For a full disclosure of my invention, reference is made to the following specification and accompanying drawings, in which:

25 Figure 1 illustrates diagrammatically a multiple fixture refrigeration system embodying the present control system;

30 Figure 2 shows a modified system similar to that of Figure 1, but using only a single evaporator and a differently located by-pass; and

35 Figure 3 shows a system somewhat similar to that of Figure 2 in which the by-pass incorporates a constant pressure reducing valve.

Referring to Figure 1, compressor 10, driven by motor 11, discharges through pipe 12 to condenser 13 and to by-pass branch 14. A liquid line 15 conveys liquified refrigerant from condenser 13 to conduits 19, 20, and 21 which connect liquid line 15 to evaporators 16, 17, and 18, respectively. Each evaporator is controlled by a thermostatic expansion valve and an associated by-pass, evaporator 16 being provided with a thermostatic expansion valve 22 and by-pass 23; evaporator 17 is provided with expansion valve 24 and by-pass 25, while evaporator 18 is equipped with expansion valve 26 and a by-pass 27. Evaporators 16, 17, and 18 are connected to main suction means 28 by suction means 29, 30, and 31, respectively.

40 Main suction means 28 may be provided with, if desired, a throttling valve 32 controlled by pressure controller 33. Compressor motor 11 may be controlled by means including switch means 34 connected to suction means 28 by tube 35. Switch means 34 is also connected to the high pressure refrigerant line 12 by tube 36. De-

vice 34 may comprise a conventional low suction pressure cut-out and a high head pressure cut-out in series therewith to prevent operation of compressor motor 11 in the event of an excessive head pressure or extremely low suction pressure. Further, said device 34 may comprise a device such as described in the patent application of Carl G. Kronmiller, Serial No. 371,001, filed December 20, 1940, now Patent No. 2,377,503, issued June 5, 1945.

Hot gas by-pass means 23, 25, and 27 are fitted with modulating valve means 40, 41 and 42, respectively. Valve means 40 is controlled by thermostatic means 43. Thermostatic means 43 comprises a volatile fluid filled bulb 44 and a connected bellows means 45, said bellows operating an arm 46 over potentiometer coil 47. Valve 41 is controlled by thermostatic device 48, similar to 43; and valve 42 is controlled by thermostatic device 49, also similar to 43. The valve means 40, 41 and 42 are each powered by a modulating motor of the sort described in the patent of D. G. Taylor, No. 2,028,110.

If desired, conduits 19, 20, and 21 may be fitted with check valves 50, 51 and 52, respectively, said check valves being located upstream in said conduits above the confluence of the by-passed refrigerant and the liquid refrigerant, said check valves permitting flow only toward their respective evaporators.

Downstream of the confluence of the by-pass 25 and liquid line 20, a fixed orifice 54 may be provided ahead of expansion valve 24. The fixed orifice is proportioned to permit only sufficient liquid refrigerant to pass therethrough to operate the associated evaporator at full capacity. This orifice supplements the control, in association with a by-pass, of thermostatic expansion valve 24. The introduction of by-passed gaseous refrigerant into the liquid line ahead of said orifice, tends to decrease the density of the refrigerant passing through said orifice and the expansion valve, and thereby results in a lesser flow, by weight, of refrigerant to the associated evaporator, thereby resulting in less refrigeration being possible at said evaporator. Further, the heat of the refrigerant is increased by the admixed hot gases, hence less heat must be added to same to give a predetermined number of degrees of superheat. The orifice also helps to uniformly mix the gaseous and liquid refrigerant. As the thermostatic expansion valve also forms, in effect, an orifice, supplementary orifice means may be used or not as a matter of choice.

The relation and action of the various parts will be further illustrated in the following operation schedule.

Operation of Figure 1

With the switches in device 34 in closed position, motor 11 may be started in any convenient manner such as by closing switch 60, the circuit being: line 61, wire 62, switch 60, wire 63, switch device 34, wire 64, motor 11, wire 65, and line 66.

With motor 11 and compressor 10 operating, gaseous refrigerant is discharged through pipe 12 into condenser 13 and to by-pass line 14. Heat is extracted from the refrigerant in condenser 13 in any convenient manner and the refrigerant is thereby liquified. Liquid refrigerant from condenser 13 is led to the evaporators by branch 15, evaporator 16 obtaining its refrigerant from branch 15 through conduit 19, including check valve 50 and thermostatic expansion valve 22, said refrigerant being exhausted through

suction means 29 to main suction means 28. Bellows 45, as shown, is in a fully retracted position due to the satisfied condition of the medium cooled by evaporator 16; bulb 44, connected to bellows 45, being responsive to the temperature of said medium. Arm 46 is therefore at the extreme left of potentiometer coil 47 and has driven motor valve 49, normally closed, to a wide open position. With valve 49 open, a flow of gaseous refrigerant enters conduit 19, mixes with liquid refrigerant from branch 15; and the mixture passes on to feed expansion valve 22, evaporator 16, pipe 29 and main suction means 28. With small flows of hot gas and with sub-cooled liquid refrigerant, the gas will tend to liquify and the amount of sub-cooling will be lessened. At large flows of gaseous refrigerant, where the amount of sub-cooling is insufficient to liquify said gas, a mixture of gaseous and liquid refrigerant results. Under some conditions, the by-passed gaseous refrigerant may enter conduit 19 at a pressure exceeding that of the refrigerant in pipe 15, thus preventing flow from 15 into 19. However, check valve 50 prevents the by-pass gases from flowing into 15, thus preventing said by-pass from interfering with the control of other evaporators. The flow of gaseous refrigerant through evaporator 16 prevents that evaporator from being pumped down to a low pressure and temperature. Expansion valve 22 tends to maintain an open position as the by-pass gases are added to the liquid refrigerant, for the higher the percentage of gas entering the evaporator, the less the heat needed to give the required number of degrees of superheat to open said expansion valve. Under extreme conditions in which hot, gaseous refrigerant only is flowing through the expansion valve, the valve may remain wide open, the rate of flow being limited by friction and by the restrictions offered by valve 22 and other means. By raising the temperature of the evaporator its cooling effect is lessened, thereby providing temperature control of the medium being cooled. The capacity of each hot gas by-pass may be limited in such manner that the maximum amount of gas passing through same will be only that necessary to control the associated evaporator. Such limiting means may comprise an orifice or other such restriction in the gas line or may comprise an adjustment of the electrical means controlling the modulating valve in such manner that the valve can only be opened a desired amount.

Thermostatic bulb 71 and its associated bellows 72, responsive to the conditions of the medium cooled by evaporator 17, have driven arm 73 to about the mid point of coil 74, thereby driving valve 41 partially open. With valve 41 partially open, hot gas flows through pipe 14, by-pass line 25 and into conduit 20 where it mixes with liquid refrigerant flowing from branch 15 into said conduit 20. The mixture of gas and liquid refrigerant flows through orifice 54 where it is further mixed, and then through expansion valve 24, evaporator 17 and pipe 30 into main suction means 28. Because the density of the refrigerant passing through orifice 54 has been lowered by the introduction of gaseous refrigerant the total quantity of refrigerant flowing through expansion valve 24 and evaporator 17, is reduced and the heat of same is increased, hence comparatively little heat is required to be added through the evaporator to give sufficient superheat to open the expansion valve 24 and raise the pressure and temperature within the evapo-

rator. The capacity of evaporator 108 is thereby controllably reduced.

Bulb 16 and bellows 17 of the thermostatic device 14 indicate a condition of maximum demand and arm 18 is at the extreme right of coil 19, whereby valve 42 remains in closed position and no gas is by-passed. Refrigerant, therefore, passes through pipe 15, conduit 21, thermostatic expansion valve 26, evaporator 18 and pipe 31 to main suction means 28 in a conventional manner and evaporator 18 operates at full capacity.

If used, the throttling valve 32 introduced in main suction means 28 is controlled by pressure controller 33 in such manner that the suction pressure imposed on compressor 10 may be limited to a predetermined high limit, thereby protecting said compressor against unduly high suction pressure brought about by said by-passing of gaseous refrigerant. Under some conditions, however, this control is not needed for the power demand of a compressor rises with increased suction pressure only to a predetermined amount and with further rise in suction pressure, power consumption falls off.

Figure 2

In Figure 2, compressor 101, driven by motor 162, discharges through pipe 103 to condenser 104 and by-pass line 105. Condenser 104 supplies liquid refrigerant through pipe 106 to thermostatic expansion valve 107 and evaporator 108, said evaporator being connected by main suction means 109 to compressor 101. Compressor 101 is protected by a device 110 similar to 34 in the above example, said device 110 being connected to suction means 109 by tube 111, and to high pressure pipe 103 by tube 112. By-pass 105 is fitted with a normally closed modulating valve 113 under the control of thermostatic device 114, said by-pass 105 being connected to evaporator 108 immediately down stream of expansion valve 107. Thermostatic expansion valve 107 may be of the conventional sort, but preferably has its pressure chamber connected to suction means 109 by equalizer line 115, there being less pressure fluctuation at the exhaust end of evaporator 108 than at the head end when the by-pass means are used for control.

Thermostatic device 114 comprises bellows 116 and an associated volatile fluid filled bulb 117, said bellows 116 actuating an arm 118 and moving same over potentiometer coil 119.

Operation of Figure 2

As in the previous example, compressor 101 and its motor 102 may be controlled in any convenient manner such as by manual switch 120, the circuit controlling motor 102 being: current supply wire 121, wire 122, switch 120, wire 123, switch device 110, wire 124, motor 102, wire 125, and current supply wire 126.

With the switches of device 110 in closed position and manual switch 120 closed, motor 102 and compressor 101 are in operation, said compressor 101 discharging through pipe 103 into condenser 104 and by-pass line 105. With valve 113 closed, refrigerant from condenser 104 passes through line 106, expansion valve 107, evaporator 108, suction means 109 and into compressor 101 in a conventional manner. Expansion valve 107 is constructed to maintain a predetermined number of degrees of superheat at the exit of evaporator 108. As before indicated, with valve 113 closed and no by-passing of refrigerant taking

place, the system is operating at full capacity. With light load and normal control this would result in frequent stopping and starting of the compressing equipment due to the suction switch means of device 110, and thus cause undue wear and tear on mechanism. In the present example as the demand becomes partially satisfied, arm 118 is drawn across coil 119 and operates valve 113 from closed to open position thereby permitting by-passing of refrigerant through pipe 105 to evaporator 108. In the position shown, arm 118 is about half way across coil 119, hence, valve 113 is partially open; hot gas is being bypassed into evaporator 108 where it adds heat and raises the pressure therein. As the pressure within the evaporator is increased, its temperature is likewise increased and its cooling effect is lessened, thereby making possible the balancing of the refrigeration supplied and the load demand and permitting continuous running of the mechanism. When the demand for refrigeration, as determined by thermostatic device 114, becomes satisfied, arm 118 is advanced across coil 119 and moves valve 113 toward open position thereby by-passing more gas to said evaporator. An increase in demand causes an expansion of bellows 116 and drives 118 toward the left of 119 thereby driving valve 113 toward closed position and permitting full capacity of the system as previously described.

In summary, a conventional system, as shown in Figure 2, may be controlled by varying the pressure within the evaporator by by-passing gaseous refrigerant thereinto. By increasing the pressure within an evaporator, the temperature of same will automatically be raised, thereby lessening its cooling effects. Further, by action of the thermostatic expansion valve means, the gas passing from the evaporator has a temperature only a predetermined number of degrees above that corresponding to the pressure of the refrigerant within the evaporator and therefore within a safe limit for induction into compressor 101.

Figure 3

Figure 3, as noted, also shows by-pass control of a single evaporator. However, the system shown in this figure may be used for plural evaporator installations wherein the lower limit of temperature desired for each of the evaporators is the same.

In this figure, compressor 151 is driven by motor 152 and discharges through pipe 153 to condenser 154 and by-pass pipe 155. Condenser 154 supplies liquid refrigerant through pipe 156 to thermostatic expansion valve 157 and its associated evaporator 158, said evaporator 158 being connected by suction means 159 to compressor 151. Hot gas by-pass 155 includes a pressure reducing valve of the constant pressure type, 160, said by-pass connecting to evaporator 158 just down stream of expansion valve 157. Motor 152 is protected against overload by high pressure cut-out 161 connected to line 153 by tube 162. The operation of the motor is controlled by thermostatic device 163 operating in series with device 161. Thermostatic device 163 comprises bellows 164 and an associated bulb 165, said bellows actuating mercury switch means 166 in such manner that when a refrigeration demand is satisfied, contact is broken in said switch. When there is a demand for refrigeration, contact is made by said switch. The operation of the sys-

tem thus outlined will be brought out in the following schedule.

Operation of Figure 3

The system of Figure 3, as above outlined, has less flexibility of control than does the previous example. However, under some conditions, flexibility of control may be properly sacrificed by the protection characteristics inherent with the system of this figure in a manner that will become apparent.

Upon a demand for refrigeration, as determined by thermostatic device 163, mercury switch 166 closes a circuit and the compressor is started as follows: current supply wire 170, wire 171, mercury switch 166, wire 172, high pressure cut-out 161, wire 173, motor 152, wire 174, and current supply wire 175. Assuming that valve 160 in by-pass 155 is closed, refrigeration takes place in a conventional manner. Gaseous refrigerant is compressed in compressor 151, discharged through pipe 153 into condenser 154, and heat is removed from said refrigerant in said condenser in the usual manner, thus liquifying said refrigerant. Liquid refrigerant from condenser 154 goes through pipe 156 to thermostatic expansion valve 157 which feeds refrigerant into evaporator 158 wherein it is evaporated by heat extracted from the medium being cooled, and the resulting gaseous refrigerant goes through pipe 159 back to compressor 151 to be further compressed and to complete the cycle. Thermostatic expansion valve 157 adjusts the flow of refrigerant to evaporator 158 in such manner that the refrigerant flowing out of evaporator 158 will have a predetermined number of degrees of superheat. Under light loads, with a system functioning in a conventional manner as above outlined, compressor 151 will be frequently stopped and started in response to thermostatic device 163. Further, with light loads, the flow of refrigerant through thermostatic expansion valve 157 is considerably reduced and compressor 151 tends to pump evaporator 158 down to very low pressures. Under some conditions of cooling, this is not objectionable; but in other cases the very low suction pressures obtained result in bad running of the compressor and also result in excessive dehumidification of the medium being treated by said evaporator. It is the function of by-pass 155 and its associated valve 160 to provide a lower limit of pressure and temperature for said evaporator 158 to thereby limit the dehumidifying effect of said evaporator and to protect said compressor from unduly low operating pressure.

In practice, the lowest pressure and temperature desired at said evaporator 158 is determined, both from the standpoint of dehumidification and from the effect on the compressing equipment. With a pressure for 158 determined, valve 160 is set to open at that pressure. In operation, the system as thus outlined will operate in a strictly conventional manner until the evaporator pressure reaches the predetermined low limit, at which point valve 160 opens and permits hot gaseous refrigerant to flow through by-pass 155 into said evaporator in sufficient quantities to maintain said predetermined pressure. The minimum pressure of the evaporator being limited, the minimum temperature is also limited and its ability to dehumidify air being treated, or product being cooled, is limited. Obviously, valve 160 may be set to open at any desired pressure. As before stated, a system of this sort may be used with a multiple evaporator installation

if each of the evaporators has the same lower limit of pressure and temperature.

In the examples of the invention above described, the systems have been controlled by means responsive to temperature, but this is to be considered as illustrative only and not limiting the scope of the invention. Obviously, other condition responsive means such as humidity sensitive devices may be used instead of the thermostats shown and the present systems may be regulated to govern humidity rather than temperature. In the present case, psychrometric is considered descriptive of both temperature and humidity conditions. The protection means illustrated for the compressor motors is to be considered as illustrative only as these controls may be dispensed with, or any other conventional controls may be substituted therefor.

Many other modifications and adaptations of the present invention are readily apparent to one skilled in the art, hence the scope of the invention is to be determined by the following claims:

I claim as my invention:

1. In a refrigeration system, means controlling the capacity of an evaporator comprising a thermostatic expansion valve for controlling the flow of fluid to said evaporator, means for varying the density of refrigerant supplied to said thermostatic expansion valve means, and orifice means limiting the volume of said variable density refrigerant supplied to said expansion valve.

2. In a refrigerating system, in combination, a source of gaseous refrigerant under pressure, a supply of liquid refrigerant under less pressure, an expansion valve of the superheat responsive type, an evaporator, conduit means connecting said supply of liquid refrigerant to said expansion valve and evaporator, by-pass means comprising a valve connecting said source of gaseous refrigerant to said conduit at a point up-stream of the expansion valve, and means responsive to a psychrometric condition in control of said by-pass valve.

3. In a refrigerating system, a source of gaseous refrigerant under pressure, a supply of liquid refrigerant under less pressure, a thermostatic expansion valve, an evaporator, conduit means connecting said supply of liquid refrigerant to said expansion valve and evaporator, by-pass means comprising a valve connecting said source of gaseous refrigerant to said conduit at a point up-stream of said expansion valve, means responsive to a psychrometric condition in control of said by-pass valve, and fixed orifice means in said conduit between the junction of said by-pass means and conduit means and said expansion valve.

4. In a refrigerating system, a source of gaseous refrigerant under pressure, a supply of liquid refrigerant under less pressure, a plurality of evaporators, expansion valve means for each of said evaporators for controlling refrigerant flow thereto, conduit means connecting said supply of liquid refrigerant to said expansion valve means and said evaporators, and orifice means proportioned to pass sufficient liquid refrigerant to give the desired maximum refrigerating capacity to an associated evaporator, said orifice means being located up-stream from the expansion valve associated with said evaporator.

5. In a refrigerating system, a source of gaseous refrigerant under pressure, a supply of liquid refrigerant under less pressure, a plurality of evaporator means, conduit means including a plu-

rality of expansion valve means connecting said supply of liquid refrigerant to said plurality of evaporator means, flow limiting restriction means in said conduit means up-stream of at least one of said expansion valve means, and by-pass means including valve means connecting said source of gaseous refrigerant to said conduit means up-stream of said expansion valve means and up-stream of said restriction means.

6. In a refrigerating system, means supplying gaseous refrigerant under pressure, means supplying liquid refrigerant under less pressure, a plurality of evaporators, thermostatic expansion valve means for controlling each of said evaporators, conduit means connecting said liquid refrigerant supply means to said expansion valve means and said evaporators, and means mixing said compressed gaseous refrigerant with said liquid refrigerant up-stream of said expansion valve means to vary the density of the refrigerant passed through the same.

7. In a refrigerating system, means supplying gaseous refrigerant under pressure, means supplying liquid refrigerant under less pressure, a plurality of evaporators, thermostatic expansion valve means for controlling each of said evapor-

tors, conduit means connecting said liquid refrigerant supply means to said expansion valve means and said evaporators, a plurality of bypass means for mixing said gaseous refrigerant with said liquid refrigerant upstream of said expansion valve means to vary the density of the refrigerant passed through the same, and means including condition responsive means for controlling each of said by-pass means.

10 8. In a refrigerating system, in combination, a source of gaseous refrigerant under pressure, a supply of liquid refrigerant under less pressure, evaporator means, an expansion valve means for controlling refrigerant flow through said evaporator means, conduit means connecting said means supplying liquid refrigerant to said expansion valve means and said evaporator means, and bypass means including valve means for mixing said compressed gaseous refrigerant with said liquid refrigerant up-stream of said expansion valve means for varying the density of the refrigerant passed through said expansion valve means, said by-pass valve means being of the two way sort and controlling the flow of the gaseous refrigerant.
